Attn's.

UNITED STATES PATENT OFFICE.

ALBERT E. WING, OF CLEVELAND, OHIO.

DESIGN FOR A VEHICLE-TIRE.

52,232.

Specification for Design. Patented July 23, 1918.

Application filed April 22, 1918. Serial No. 230,139. Term of patent 3½ years.

To all whom it may concern:

Be it known that I, ALBERT E. WING, a citizen of the United States, and a resident of Cleveland, in the county of Cuyahoga and State of Ohio, have invented a new, original, and ornamental Design for Vehicle-Tires, of which the following is a specification, reference being had to the accompanying drawing, forming part hereof, wherein

the figure is a front elevation of a portion of a vehicle tire embodying my invention.

What I claim is:—

The ornamental design for a vehicle tire as shown.

ALBERT E. WING.

Witness:

K. N. SOMMERS.
